CLAIM

The ornamental design for a loop-handle for cooking utensils and apparatus, as shown and described.

DESCRIPTION

FIG. 1 is an upper perspective view of a loop-handle for cooking utensils and apparatus showing our new design;
 FIG. 2 is a lower perspective view thereof;
 FIG. 3 is a front view thereof;
 FIG. 4 is a rear view thereof;
 FIG. 5 is a top view thereof;
 FIG. 6 is a bottom view thereof;
 FIG. 7 is a left side view thereof; and,
 FIG. 8 is a right side view thereof.

The portions of the loop-handle for cooking utensils and apparatus shown in broken lines form no part of the claimed design.
